DISPLAY STAND

Filed Feb. 24, 1932

UNITED STATES PATENT OFFICE

CHARLES E. LITTLE, OF MELROSE, MASSACHUSETTS, ASSIGNOR TO DOVER STAMPING & MANUFACTURING COMPANY, OF CAMBRIDGE, MASSACHUSETTS, A CORPORATION OF MASSACHUSETTS

DISPLAY STAND

Application filed February 24, 1932. Serial No. 594,366.

The invention relates to a stand on which may be displayed vendible commodities and especially bottles containing oil, the stand being especially designed for stations where oil is dispensed.

The objects of the invention are as follows: To provide a display stand of sectional character composed of units which may be assembled into a variety of forms; to provide also a unit stand complete in itself but which is capable of being easily and quickly combined with other like unit stands to form a stand assembly; to provide also a unit stand of simple construction, one possessing proper strength and rigidity, and composed of detachable parts by which it, or the parts of all assembled units when knocked down or disassembled, may be reduced to the form of a relatively small carton.

The invention can best be seen and understood by reference to the drawing, in which—

Figure 1 shows in perspective an embodiment of the invention in one of its preferred forms composed of three units.

Fig. 2 is a cross section on the line 2—2 of Fig. 1.

Fig. 3 is a plan of a detail of construction.

Figs. 4 and 5 show mainly in plan constructive details to which special reference will later be made, and

Fig. 6 shows partly in vertical cross section, partly in side elevation and partly in perspective further elements to which reference will, also, later be made.

The essence of the invention resides in the construction of the individual units of the display stand, forming as each does a display stand complete in itself, yet one capable of being combined with one or more like units to form an assembled structure. Accordingly description will first be made of the individual unit referred to as a display stand complete in itself.

The body of the stand comprises a frame 1 preferably rectangular in form and made of angle iron having sectional parts 2 and 3. Of these the part 2 occupies a vertical position and the part 3 a horizontal position with extension inwardly from the lower end of

2. The frame is formed by bending the angle iron, the free ends 4 and 5, respectively, of its part 2 being made to overlap and the ends secured by riveting. The outer side or face of the frame presents a finished appearance and in order that this effect may prevail at the point of its overlapping ends, the end 4 is preferably offset with relation to the end 5 as shown in Fig. 3. The frame is reinforced by crossbars 6 the ends of which overlap the sectional parts 3 of the frame along either side thereof and are secured thereto by riveting.

Extending lengthwise the frame 1 to rest upon its crossbars 6 and with sufficient extension to overlap the parts 3 of the frame 1 at its opposite ends is a plate 7. Thus constructed the body forms a support in the nature of a tray, the section part 2 of the frame forming the sides of the tray and the section part 3 thereof supplemented by the plate 7 forming the bottom of the tray.

The body of the stand is maintained in a raised or elevated position, being mounted upon detachable legs 8. The legs are secured to the stand body so that it may be supported by them in the following manner:

Arranged at each of the several corners of the frame 1, where the metal is bent at substantially right angles, are disposed posts 9 preferably tubular in form. These posts rest snugly within the bends formed by the sectional part 2 of the frame and extend through the sectional part 3 thereof. The posts are relatively short rising to a point where their tops will lie substantially flush with the top edge of the frame and with downward extension to a point just below the bottom of the frame. The posts are held securely in place by the sectional part 3 of the frame through which they are extending. To this end, and to permit also of the bending of the angle iron of which the frame is made, the sectional part 3 of the frame is provided with notches 10 with curved ends 11 bounding the notches. (See Fig. 4.) Each of the posts 9 is provided with an annular groove 12. When the posts are in place these grooves will lie in the

plane of the sectional part 3 of the frame, and as the frame is bent it will envelop the posts at the points of the notches and the curved ends 11 of its sectional part 3 will 5 enter the annular grooves 12 in the posts to snugly embrace them and thereby securely hold the posts in place. (See Fig. 5.)

Formed in the bottom sectional part of each of the posts is a threaded socket 13 and 10 into these sockets for the several posts the top ends of the legs 8 made threaded are adapted to fasten.

At points adjacent their bottom ends the legs are preferably tied together by cross- 15 bars 15. These bars are preferably united at their central crossing points 16 by riveting and at their outer ends bear collars 17 which slip onto the respective legs and are secured by binding screw and nut connec- 20 tions 18.

In their top sectional parts each of the posts 9 is provided with a socket 19 into which may fit the bottom end of any one of the legs 8 of an adjacent unit like the one 25 above described. In other words, several unit stands having been provided they may be assembled by placing the bottom ends of the legs of a superposed unit or units within the sockets 19 of posts to units on 30 which the mounting is made, thus permitting of considerable variation in the assembly of units of which the assemblage of units shown in Fig. 1 is but an example.

Having thus fully described my invention, 35 I claim and desire to secure by Letters Patent of the United States:—

1. A display stand comprising a body having a frame of angle iron with one part section arranged vertically and the other 40 part section arranged horizontally with extension inwardly from the lower end of the vertical section, said horizontally arranged section having a plurality of openings, a post secured in each of said openings, and 45 legs detachably secured to said posts.

2. A display stand comprising a body having a frame of angle iron with one part section arranged vertically and the other part section arranged horizontally with extension inwardly from the lower end of the 50

vertical section and provided with notches at the corners of the frame, posts arranged within said notches, means for fixedly retaining the posts, and legs connecting with said posts. 70

3. A display stand comprising a body having a frame of angle iron with one part section arranged vertically and the other part section arranged horizontally with extension inwardly from the lower end of the 75 vertical section and provided with notches at the corners of the frame, posts arranged within said notches with edge portions of said horizontal section of the frame adjacent said notches having socketed engagement 80 with said posts, and legs connecting with said posts.

4. A display stand comprising a body having a frame of angle iron with one part section arranged vertically and the other 85 part section arranged horizontally with extension inwardly from the lower end of the vertical section and provided with notches at the corners of the frame, the portions of said horizontally-extending section of the 90 frame bounding the notches presenting curved edges, posts arranged within the notches, each of said posts being provided with an annular groove into which said curved edges extend, and legs connecting 95 with said posts.

5. A display stand comprising a plurality of assembled units, each comprising a body having a frame of angle iron with one part section arranged vertically and the other 100 part section arranged horizontally with extension inwardly from the lower end of the vertical section and provided with notches at the corners of the frame, legs supporting said frame, posts arranged within said 105 notches with edge portions of said horizontal section of the frame adjacent said notches having socketed engagement with said posts, each of said posts having in it a plurality of sockets, one in the bottom section of the post 110 adapted to receive the top end of one of said legs, and the other in the top section of the post adapted to receive the bottom end of the leg of an adjacent one of said units. 115
